CLOTHES RACK

Joseph V. Cummiskey, 416 E. 14th St.,
Elmira Heights, N.Y.

Filed Dec. 18, 1961, Ser. No. 67,948

Term of patent 3½ years

(Cl. D33—8)

FIGURE 1 is a side elevational view of a clothes rack embodying my new design, the fragmentary broken-line representation of a door being for purposes of illustration only.

I claim:

The ornamental design for a clothes rack, substantially as shown and described.
